Patented July 23, 1918.

FIG. 2

Inventor

Bryson Dexter Norton,
By his Attorney
Clifford S. Johnson

UNITED STATES PATENT OFFICE.

BRYSON DEXTER HORTON, OF DETROIT, MICHIGAN.

CONNECTOR.

1,273,224.

Specification of Letters Patent. Patented July 23, 1918.

Application filed August 31, 1916. Serial No. 117,829.

To all whom it may concern:

Be it known that I, BRYSON DEXTER HORTON, a citizen of the United States, residing in the city of Detroit, county of Wayne, and 5 State of Michigan, have invented certain new and useful Improvements in Connectors, of which the following, taken in connection with the accompanying sheet of drawings, is a full, clear, and concise 10 description thereof.

My present invention constitutes an improvement upon the construction illustrated and described in a copending application heretofore filed by one Frederick Zenker 15 and myself on July 14, 1916, bearing Serial Number 109,280.

My invention comprehends new and improved means for effectively connecting a member of thin blade-like construction to a 20 supporting member and adapts itself particularly for effecting substantial rigidity in the movable contacts of a switch construction to insure the maintenance thereof in perfect alinement with respect to the co-operating stationary contacts.

Another object of my invention is to produce a simplified and inexpensive form of connecting device for associating a plurality of movable members to enable them to be 30 operated in unison.

In the accompanying drawings, I have illustrated by way of example one preferable embodiment of the features and principles of my invention, in which—

35 Figure 1 is a view in perspective of a two-pole single-throw switch, embodying such preferred form of my invention.

Fig. 2 is a fragmentary enlarged detail 40 of parts of the switch illustrated in Fig. 1.

Fig. 3 is a view in perspective of one of the connecting devices employed for fastening the insulating cross-head to the knife-blade contacts.

Referring in detail to the drawings, 1 45 indicates a base preferably made of porcelain or other insulating material upon which are mounted the stationary contacts 2 of jaw form and pivoted supports 3 for knife-blade contacts 4. The switch illustrated being of the two-pole single-throw type, a pair of knife-blade contacts are employed, these being operably associated through the medium of the cross-head 5, which is preferably made of insulating material and for 55 convenience of application is rectangular in cross-section. In order to operate the knife-

blade contacts in such a way as to apply the operating power in a balanced manner, a crank 6 having an extremity 7 is provided, which is received within the eye of the connecting member 8, this connecting member being preferably located midway between the knife-blade contacts and taking the form of a screw-eye bolt, which is threaded through and extends beneath the cross-head 65 5 and retained in place by a nut. The crank 6 is pivotally mounted at 9 in one side of a protecting housing 10 and at a point substantially in alinement with the pivot points 11 of the knife-blade contacts. Moreover, the crank is provided with an exterior 70 arm 12, which extends substantially parallel with and in a plane common to the side of the casing and serves to afford means whereby the switch may be manipulated. The cross-head 5 is located across and above the knife-blade contacts, and the extremities thereof extend beyond the outer sides of said knife-blade contacts. The ends of the cross-head are provided with rectangular apertures 80 conforming in shape to the upwardly-extending tangs 13 of the connecting devices which are used to connect the cross-head with the knife-blade contacts, these tangs being received within the apertures 85 of washer-like members 14 which are placed thereover, whereupon the ends of the tangs are riveted down as at 14' to securely fasten the connecting device to the cross-head. Near the lower extremities of these connecting devices are the laterally-extending tangs 15, which are received in conforming apertures provided in the knife-blade contacts 4, after which the ends of the tangs 15 are 90 riveted down to securely fasten the knife-blade contacts thereto. In order to secure increasing rigidity to this form of connection, the connecting device is provided with a pair of depending lugs or projections 16, which bear against the inner sides of the 100 knife-blade contacts. The tang 13 is of less width than the greatest width of the device, thus providing the shoulders 13', which fit against and beneath the cross-head, so as to afford increasing rigidity to the connection. 105

It will be observed that the connecting device is formed from a single stamping of sheet metal, making an inexpensive switch part which forms a substantial connection between the cross-head and the knife-blade 110 contacts.

While I have illustrated and described one

preferable structure in which my invention may find embodiment, I do so by way of example only as changes may be resorted to without departing from the spirit and scope 5 of my invention as defined by the following claims.

Having thus described my invention, what I claim as new herein and desire to secure by Letters Patent is:—

- 10 1. A connecting device embracing a cross head and fastening means comprising a sheet metal connector having fastening lugs extending through the cross head and riveted thereover, and fastening lugs extending at right angles thereto extending through the parts to be connected and having the ends riveted thereover.
- 15 2. A connecting device embracing a cross head made of insulating material and having its extremities extending beyond the outer edges of parts to be connected and connecting devices connecting the cross head to the parts to be connected, each connecting

device comprising a sheet metal plate having a tang extending through the cross head 25 with its end riveted thereover, a laterally-extending tang extending through one of the knife-blade parts to be connected and having its end riveted thereover and a pair of depending projections bearing upon such 30 part to add rigidity to the connection as a whole.

3. A connector comprising a sheet metal device having a reduced tang adapted to be received within an aperture of a part to be 35 connected and to be riveted thereover, a laterally-extending tang substantially of equal width with said first-mentioned tang and adapted to be received in an aperture provided within another part to be connected 40 and adapted to be riveted thereover, said latter tang being stamped and bent from the body of the connector at a point substantially in vertical alinement with the said first-mentioned tang.

BRYSON DEXTER HORTON.
